COMBINED FAN AND ELECTRIC HEATER

Ray R. Hutcheson, Brooklyn, N. Y., assignor to
E. A. Laboratories, Inc., Brooklyn, N. Y., a corporation of New York

Application April 29, 1948, Serial No. 146,021

Term of patent 14 years

(Cl. D26—7)

To all whom it may concern:

Be it known that I, Ray R. Hutcheson, a citizen of the United States, residing at Brooklyn, in the county of Kings and State of New York, have invented a new, original, and ornamental Design for a Combined Fan and Electric Heater, of which the following is a specification, reference being had to the accompanying drawing, forming a part thereof, wherein:

Fig. 1 is a rear elevational view of a combined fan and electric heater, embodying my new design;

Fig. 2 is a side elevation thereof;

Fig. 3 is a front elevational view thereof; and

Fig. 4 is a perspective view of the base with the combined fan and electric heater cut away.

The opposite side elevation is similar to Fig. 2.

The dominant features of the design are shown in that part of the drawings which is in solid lines.

I claim:

The ornamental design for a combined fan and electric heater, substantially as shown and described.

RAY R. HUTCHESON.
